United States Patent Office

Des. 199,734
Patented Dec. 8, 1964

199,734

BRAKE SHOE ANCHOR

Lloyd D. Kay, San Marino, Calif., assignor to Kay-Brunner Steel Products, Inc., Alhambra, Calif., a corporation of Delaware

Filed Feb. 27, 1963, Ser. No. 73,739

Term of patent 14 years

(Cl. D14—30)

FIG. 1.

FIG. 2.

FIG. 3.

FIG. 4.

FIG. 5.

FIGURE 1 is a perspective view of a brake shoe anchor embodying my new design;

FIGURE 2 is a bottom plan view of the brake shoe anchor as shown in FIGURE 1;

FIGURE 3 is an elevational view of the side opposite that shown in FIGURE 1; and

FIGURES 4 and 5 are elevational views of the opposite ends of my new design.

I claim:

The ornamental design for a brake shoe anchor, as shown.
